PRESSURE SENSITIVE SWITCH

Louis B. Courtot, Cleveland, Ohio, assignor to The Weatherhead Company, Cleveland, Ohio, a corporation of Ohio

Application January 24, 1956, Serial No. 561,047

2 Claims. (Cl. 200—83)

This invention relates to a switch device responsive to the application of fluid pressure to make a contact between spaced electrical terminals for the completion of an electrical circuit.

It is an object of my invention to provide an improved pressure responsive switch of simplified construction.

It is a further object of my invention to provide a resilient diaphragm means on which is mounted a metallic surface for completing an electrical circuit.

It is an object of my invention to provide a simplified fluid pressure switch which can be readily used in a hydraulic braking system of an automobile so that the application of fluid pressure acts upon a resilient diaphragm means to close the switch, and the release of fluid pressure allows the diaphragm to restore itself to its initial position thereby opening said switch.

It is a further object of my invention to provide a novel securement means for the diaphragm means of a fluid pressure switch.

It is an object of my invention to provide an electrical conducting means suitably mounted on a self-restoring diaphragm means wherein the electrical conducting means is caused to make contact with the switch terminal upon application of fluid pressure, and upon release of said fluid pressure the self-restoring diaphragm means moves the electrical conducting means away from said switch terminals.

These and other objects and advantages will appear from the following description relating to the drawings of which:

Fig. 1 is a sectional elevation of the pressure switch device;

Fig. 2 is a sectional view taken at 2—2 of Fig. 1;

Fig. 3 is a sectional elevation showing the pressure switch of Fig. 1 in contact position;

Fig. 4 is a partial section of the diaphragm arrangement before securement;

Fig. 5 is a modified form of a pressure switch shown in section; and

Fig. 6 is the pressure switch of Fig. 5 shown in contact position.

Referring to Fig. 1, a round metal body 10 is provided with an annular recess 11 communicating with a passageway 12. Said passageway 12 is located in a threaded stem portion 12a of body 10 and is adapted to communicate fluid pressure to recess 11 from a pressure system not shown. Located within body 10 is a block 13 of rigid electrical insulating material such as a phenolic resin. Molded within block 13 are two electrical terminals 14 and 15 which are provided with plug-type projecting ends at one end, with the other end of the terminals extending into a block recess 16.

A diaphragm 17 of molded synthetic rubber-like material which is not adversely affected by hydraulic fluid is secured between block 13 and an annular inclined recess 11a of body 10.

Fig. 4 discloses the diaphragm 17 with peripheral rib

2

18 resting on the annular inclined recess 11a prior to assembly of block 13 and body 10. When block 13 is inserted into body 10 and flanges 10a are crimped into shoulder groove 13a to hold block 13 in position, the peripheral rib 18 is biased outwardly along the incline of groove 11a. This action at the peripheral rib 18 is shown in Figs. 1 and 3, and eliminates the formation of a wrinkle or the fold forming at the reduced radially inward portion of the diaphragm 17 by placing this area under a slight tension in the non-pressurized state. Such wrinkling would affect the life of the diaphragm and make it more difficult to obtain prescribed characteristics from the diaphragm when subjected to fluid pressures.

Diaphragm 17 formed to provide peripheral rib 18 is also formed to provide a central stem portion 19 extending normal to the diaphragm and proportioned axially to normally bear against the insulating block 13 at a central recess 13b. Surrounding stem 19 and in flat contact with diaphragm 17 is an annular metal disc 20 which is snapped on stem 19 and may be secured thereto by seating in an annular groove on the base of the stem. The disc 20 is arranged to be positioned toward and away from terminals 14 and 15 by the fluid pressure actuation of diaphragm 17, and when so contacting said terminals the switch is in the closed position.

In operation, body 10 is placed in communication through passage 12 with a hydraulic fluid system such as for example might be utilized in an automobile braking system. The hydraulic fluid pressure is effective when the brake is applied to move the diaphragm 17 to the position shown in Fig. 3. The movement of the diaphragm 17 in response to fluid pressure upsets the stem 19 so that it nearly fills the recess 13b of insulating block 13. The shortening of the stem 19 by the diaphragm movement causes the annular metal disc 20 to contact the electrical terminals 14 and 15 to close the circuit through the switch. Upon the release of fluid pressure from chamber 11, the diaphragm 17 is restored to its original position by the resiliency in the stem portion 19 and in the body of the diaphragm.

Fig. 5 is a modification of the pressure switch wherein the body 23 surrounds rigid insulating block 24 of phenolic resin with electrical terminals 25 and 26 molded therein.

Body flanges 23a are crimped over shoulder 24a of block 24 to secure a diaphragm 27 at its periphery between 23 and block 24.

A passageway 28 is formed in the body communicating with the one side of a diaphragm 27 for the application of fluid pressure to the diaphragm. Diaphragm 27 is shown provided with a central portion 29 extending normal thereto and having a rounded end disposed in a recess 30 in the block 24. A cylindrical chamber 31 is shown in block 24 to accommodate the expansion of a central stem portion 29. An annular metal disc 32 is snap-fitted on that side of diaphragm 27 adjacent the terminals 25 and 26 and is maintained in position on the diaphragm by an annular ridge 33 on central stem portion 29.

The electrical terminals 25 and 26 extend into recess 24b, in which the diaphragm 27 is allowed to move when actuated by fluid pressure in chamber 23b.

A reinforcing disc 34 of a rigid plastic or metal is molded in the diaphragm to assist in resisting extrusion of the diaphragm through the central hole in disc 32 and maintaining alignment of disc 32 for simultaneous contact with terminals 25 and 26.

When fluid pressure is introduced through passageway 28, the diaphragm is moved thereby to the position shown in Fig. 5 whereby the annular metallic disc 32 makes electrical contact with terminals 25 and 26 in recess 24b to close the switch. The central portion 29 is axially

compressed and radially expanded by the movement of the diaphragm in response to fluid pressure. When fluid pressure is reduced at passage 28 the pressure induced stress in the central stem portion 29 will restore the diaphragm to its unstressed or normal condition and thus move the diaphragm 27 away from the electrical terminals 25 and 26 breaking the contact between the terminals and annular metallic disc 32.

Thus I have disclosed and described a fluid pressure switch having only a minimum of parts, and having a diaphragm switch actuating means which returns to its original position upon removal of the application of fluid pressure. Such switch presents a simplified direct acting construction that affords positive closure upon application of fluid pressure. Such switch presents a simplified direct acting construction that affords positive closure upon application of fluid pressure and positive opening from the resiliency of the diaphragm upon removal of fluid pressure from the diaphragm.

While preferred embodiments of the invention have been described in considerable detail, it will be understood that modifications and rearrangements of the parts may be resorted to without departing from the scope of the invention as defined in the following claims.

What is claimed is:

1. A fluid pressure switch comprising a metal cup having a fluid opening in the bottom thereof, a flexible rubber-like diaphragm over said opening and an integrally molded cylindrical stem extending from the diaphragm on that side of the diaphragm away from said opening, a metal disc having a central aperture, said central aperture having a diameter less than the diameter of said cylindrical stem and said disc being retained on said stem at the juncture of the stem with the diaphragm by being pressed over the cylindrical stem, a molded cylindrical plug of insulating material having a diameter corresponding to the inner diameter of the cup, said plug being disposed in said cup to press the diaphragm against the bottom of the cup at its periphery, said plug being retained within the cup by having the open end of the cup bent inwardly over the plug and a pair of spaced electric terminals molded in said cup with the inner ends of said terminals disposed at either side of said diaphragm stem

5 and adjacent said apertured metal disc, said insulating plug adjacent the diaphragm having a central opening slightly larger than the cylindrical stem of the diaphragm to receive said stem and limit its deformation when the disc on the diaphragm is moved into contact with said terminals by fluid pressure.

2. A fluid pressure switch comprising a metal cup having a fluid opening in the bottom thereof, a flexible rubber-like diaphragm over said opening and an integrally molded cylindrical stem extending from the diaphragm on that side of the diaphragm away from said opening, a metal disc having a central aperture, said central aperture having a diameter less than the diameter of said cylindrical stem and said disc being retained on said stem at the juncture of the stem with the diaphragm by being pressed over the cylindrical stem, a molded cylindrical plug of insulating material having a diameter corresponding to the inner diameter of the cup, said plug being disposed in said cup to press the diaphragm against the bottom of the cup at its periphery, said plug being retained within the cup by having the open end of the cup bent inwardly over the plug and a pair of spaced electric terminals molded in said cup with the inner ends of said terminals disposed at either side of said diaphragm stem and adjacent said apertured metal disc, said insulating plug adjacent the diaphragm having a central cylindrical opening larger in diameter than the diameter of the cylindrical stem of the diaphragm to receive said stem and limit the deformation of the stem when the disc on the diaphragm is in contact with said terminals.
